ILLINOIS

TUBULAR BOILER

Application filed April 11, 1927. Serial No. 182,567.

This invention relates to a tubular boiler for a heating system and has special reference to a gas fired boiler for hot water or steam heating systems wherein the boiler comprises a system of coils of pipe so constructed and arranged as to obtain a rapid general circulation of the steam or hot water with a maximum exposure of the coils to the hot gases.

10 The present invention relates more particularly to a gas fired boiler for hot water or steam heating systems wherein the boiler comprises various coil sections heated by a gas burner, which latter is located adjacent an upper coil section from which latter the steam or hot water immediately rises to the radiators, the steam or hot water in said upper coils being replaced by preheated water or steam from the lower coil sections.

15 Further, to obtain the maximum heat from the heating gases, the burner is supplied with a mixture of gas and air under pressure which forces the hot gases through a tortuous path surrounding the coils and in the opposite direction to that of the flow of steam or water through the tubes. The mixture of gas and air under pressure displaces the stack draft of the usual type so that a slow draft is obtained, and therefore, an exhaustive utilization

20 of the heat in the hot gases.

It is well known that heat is wasted by lowering the temperature in the heating gases when the latter are permitted to expand. By providing a tortuous path and by directing the gases against coils disposed in a staggered relation and against baffle walls, the hot gases are maintained in a somewhat restricted state and are not permitted their maximum expansion. As a result thereof most of the heat in the gases is transmitted to the water or steam in the coil and a maximum of efficiency and economy is obtained.

25 One of the objects of this invention is to provide a gas fired boiler which is provided with a tortuous and obstructed path whereby the hot gases have a sluggish movement therethrough.

Another object of this invention is to provide a gas fired boiler in which the coils of pipe are so constructed and arranged as to

obtain a maximum exposure to the hot gases.

A further object of this invention is to provide a gas fired boiler comprising various sections of coils and wherein the burner is located adjacent to sections of the upper coils 55 from which the steam or hot water immediately passes to the radiators.

A still further object of this invention is to provide a gas fired boiler which is provided with a series of coils, the products of 60 combustion entering the stack after flowing through a tortuous path and contacting with said heating coils and which stack is located at or below the lowermost levels of the heating coils.

It is also an object of this invention to provide a gas fired boiler having a plurality of heating coils whereby a rapid circulation of water and steam through said coils is obtained.

70 Another object of this invention is to provide a gas fired boiler in which the burner is supplied with a mixture of gas and air under pressure whereby a slow draft and, therefore, an exhaustive utilization of the heat in the 75 gases of combustion is obtained.

Other objects and advantages of this invention will be apparent from the description and drawings forming a part of this specification to which latter reference may 80 now be had for a more complete understanding of the characteristic features of this invention, in which drawings:

Figure 1 is a side elevational view of a gas fired boiler showing the housing therefor 85 in section;

Fig. 2 is an end elevational view of Fig. 1 likewise showing the outer casing in section;

Fig. 3 is a top plan view of Fig. 1 showing the casing in section;

Fig. 4 is a plan sectional view taken on the line 4—4 of Fig. 1;

Fig. 5 is a perspective view of one of the upper coil sections;

Fig. 6 is a perspective view of one of the 95 lower coil sections; and

Fig. 7 is a plan sectional view of the boiler taken on the line 7—7 of Fig. 1 and showing the supply and control systems therefor in side elevation.

100

Referring now more particularly to the drawings, the gas fired boiler comprises a plurality of upper coil sections 10 and a plurality of lower coil sections 11 secured within an enclosure 12. The enclosure 12 preferably comprises an angle iron framework of a rectangular shape, having heat insulated metal panels enclosing the top, bottom and sides thereof.

- 10 It is preferable that each of the end walls of the enclosure 12 comprises a pair of rectangular angle iron frame members 13 and 14 having a metal plate 15 disposed therebetween. The side walls, top and bottom 15 may each comprise a single angle iron framework 15, which is bolted or otherwise secured to the rectangular frame members 13 and 14. The top and bottom of this enclosure may be made similar to the two side 20 wall members and all of these rectangular angle iron frames are provided with a heat insulating material 16 which may be of asbestos or other like material. A pair of rectangular angle iron members may be disposed 25 on the interior of the enclosure to act as an auxiliary support for the top and side walls.

The upper coil sections comprise a group of pipes 17, 18, 19 and 20 formed into coils, 30 each of said pipes comprising alternate coils lying in a horizontal plane and intermediate coils lying in a vertical plane as shown particularly in Figs. 2 and 7. The coils of the pipes extend from the front to the rear of the boiler and each pair of adjacent pipes are so arranged that the coil or one of the 35 pipes lying in a horizontal plane is disposed centrally and between the coil of the other of the pipes lying in a vertical plane. In this arrangement, the various lengths of pipe 40 lie in a staggered vertical relation.

The lower coil sections 11 comprise a group of pipes 21, 22, 23 and 24 formed into coils, 45 the pipes extending from side to side of the boiler and lying in planes one above the other. These coils are shown particularly in Figs. 1 and 2 and are supported in the aforementioned relation by means of cross supports 25 secured to the outer rectangular angle iron frame member 15.

The upper and lower coil sections are connected together at the rear end of the boiler, the lower coil 21 having an upwardly extending portion 26 of pipe 21 which is connected to a downwardly extending portion 27 of coil 17 by means of a union 28. This same connection is carried out in the various other coil sections, coil 22 being connected to coil 18, coil 23 being connected to coil 19 and coil 24 being connected to coil 20.

The other ends of the upper coil sections 17, 18, 19 and 20 are connected to a header 29 which latter is connected to the radiators, as shown particularly in Fig. 3. The lower coil sections 21, 22, 23 and 24 are similarly con-

nected at their forward ends to a header 30 which is likewise connected to the radiators. The direction of flow of the water or steam employed in the boiler is indicated by the arrows, the heating medium entering the header 30 from the radiators, continuing through the lower coil sections and thence to the upper coil sections back to the radiators through the header 29.

The lower coil sections are disposed beneath a heat insulating partition 31 and the connections between the lower coil sections and upper coil sections are in back of a baffle plate 31^a extending from the partition 31 upwardly to a position near the top of the enclosure 12. The burners used in this apparatus are of the usual type and comprise a group of four pipes 32 positioned above the partition 31 and directly beneath the lowermost or discharge end of the pipes of the upper coil sections. These pipes 32 are provided with jets 33 spaced at suitable intervals and are suitably supported on cross braces fixed to outer rectangular frame members. The lower pipe of each coil section or that pipe having direct association with the gas burner is provided with a baffle which extends half way around the upper portion of the pipe for the purpose of confining the hot gases thereto. The pipes are connected at each end to headers 32^a, one of said headers being connected to a source of gas supply which latter is mixed with air whereby a mixture of gas and air under pressure is obtained. This gas supply system and the control thereof will hereinafter be described in detail.

As the burners are operated, the hot gases strike the lowermost or discharge end of the upper coil sections which are provided with tubular baffles, and the gases are directed upwardly under pressure against the successive coils. These coils act similarly to baffle plates, the coils being in a staggered relation, and the gases are checked in their advance and are therefore considerably retarded. It may be desirable to further check the flow of the gases by providing baffle plates on the upper portions of all the coils where a smaller and a more tortuous path is afforded to the burner gases which are under pressure. After the 115 burner gases have passed around these various coils, they are directed rearwardly and over the top of the upwardly extending baffle 31^a and are then forced downwardly in the direction of the dotted arrows to the chamber in which the lower coil sections are disposed and which chamber is provided by the heat insulating partition 31. The gases pass through the bottom of this chamber and out the stack 34.

The draft thus produced by the air and gas under pressure is slow, and therefore, the hot gases are in contact with the coils for a much greater length of time than if the draft were rapid. Further, inasmuch as the burned 130

gases are retarded by reason of the tortuous path through which they have traveled, the gases are not permitted to lose the heat which would be lost were they permitted to expand, and therefore, a maximum of heat contained in the hot gases is transmitted to the water or steam in the coils.

It will be noted that the heating medium in the coils travel in the opposite direction to that of the flow of the hot gases. The burners are located adjacent the lowermost pipe of the upper heat coils, and therefore, contact with the hottest water or steam which immediately rises to the radiators. This is of great advantage, particularly in the early spring and late fall when the weather is not such that the entire supply of water in a hot water heating system need be heated in order to take the chill off the rooms in the early morning or late evening. As a result of this invention, the burners being located directly beneath the water or steam in the coils, which latter are directly associated with the radiators, the burners need only be in operation for a comparatively short time to heat a sufficient amount of water to take the chill out of the room or other enclosure to be heated and which operation will require but a minimum amount of time. It is not necessary to heat an entire drum of water or to heat the entire supply of heating medium in the heating system to do this.

It is apparent that a rapid general circulation of the steam or hot water in the coils will be obtained because of this direct connection between a small supply of water and a comparatively great supply of burned gas. The small supply of water contained in the single coil is in direct contact with a comparatively intense flame and is heated very rapidly, and therefore, passes out of the pipe very rapidly. By means of this rapid general circulation of the water or steam, there is less tendency for heat losses in the transmission throughout the heating system and therefore a great economy in the use of fuel and a great effectiveness in the use of the heat is secured.

Inasmuch as the incoming or coolest water or steam from the radiators strikes the outgoing gases at their lowest temperature, the stack loss is very low. It is preferable to have the stack located at the lowermost point of the boiler and at the farthest point from combustion. It has been stated that the air for combustion is drawn from the outside of the building in which the boiler is located. This, of course, provides for a better combustion and also precludes the necessity of drawing oxygen from the building to be so burned. When air is drawn from the building to a combustion chamber, this air must be replaced and it is usual that the replaced air leaks in through the windows, doors, etc. which provides a cooling effect and some-

times a draft in the room and are obviously very objectionable. However, it may be desirable to draw air from the outside to a recuperator or air heater, which may be adapted to be associated with the boiler in various ways known to those skilled in the art.

Referring now more particularly to Fig. 7 of the drawings, a detailed view of the means for supplying fuel to the boiler and a control system therefor is shown. It will be noted that in order to clearly illustrate the devices and the operation thereof, the gas supply conduits 35, 36, 37 and 38 together with the devices connected therebetween have been rotated through an angle of 90° so that a side elevational view thereof is obtained, where-as the boiler and its associated elements are shown in plan section.

Gas is admitted from any source of supply to a safety control valve 39 through the conduit 35 and from thence to a pressure reducing valve 40 through the conduit 36. The gas thus admitted to the reducing valve 40 usually obtains a pressure of about 6 to 8 inches of water pressure in domestic use although at intervals during the day more gas is used than at other periods which greatly reduces this pressure. As it is desirable to have a constant pressure in the operation of this system, the reducing valve 40 reduces the line pressure in this instance to about 2 inches of water pressure which pressure can invariably be maintained.

The reduced gas is next permitted to flow to the snap valve 41 through conduit 37 and from thence, when said valve is open, through the conduits 38 and 39 to the header 32^a of the burners. A gas and air mixing device 42 of any well known construction, is connected between the conduits 38 and 39 and receives air under pressure from a motor driven fan 43 which in turn is supplied with air from outside the building or other enclosure in which the apparatus is disposed. It is to be understood that the specific means for forcing the air is for illustrative purposes only and that various other well known devices may be employed as efficiently and be operated in a similar manner to that which will hereinafter be described.

The snap valve 41 is of a well known construction and it is believed that a detailed description and showing is unnecessary. However, it may be here stated that the device is controlled by means of a plunger 44 cooperating with a valve which when open permits of a quantity of gas from the conduit 37 to flow to the pressure chamber of the snap valve 41. The pressure created in the pressure chamber actuates a diaphragm to shut off the supply of gas from the conduit 37 through the lower chamber of valve 41 to the conduit 38. When it is desirable to permit a flow of gas to the burners, the valve operated by the plunger 44 is closed and the pres-

sure in the pressure chamber of the snap valve is permitted to escape through the escapement conduit 45 to be ignited by the burners or a pilot. In order to build up a pressure in the pressure chamber, the escapement conduit must have a smaller capacity than the valve operated by the plunger 44.

The plunger 44 is vertically reciprocated by means of a lever 46 to which it is suitably secured, the lever being, in turn, actuated by means of an electrically operated device 47 controlled by means of a thermally controlled device such as the room thermostat 48, the two latter devices being preferably connected in a circuit of relatively low voltage. In the operation of this latter described mechanism, when the room or other enclosure in which the thermally controlled device 48 is positioned reaches a desired temperature, an electrical circuit is completed through one side of the thermal device which controls the mechanism in the electrically operated device 47 for operating the lever 46 and thereby the plunger 44. This action opens the valve to permit a supply of gas to flow to the pressure chamber to shut off the supply of gas between conduits 37 and 38. When the room or other enclosure becomes cooled, an electrical circuit is completed through the other side of the thermal device 48 and the electrical device 47 to close the valve in the pressure chamber whereby gas is permitted to flow to the burners.

Inasmuch as the supply of fuel to the burners is not constant, it is necessary to provide a pilot light 49 which may be supplied with gas directly from the source of supply or it may preferably be by-passed from the conduit 36. The pilot light is positioned adjacent a jet at one end of the header 32^a whereafter each of the successive jets 33 are ignited therefrom. Should the pilot light be extinguished, a thermostatically controlled switch 50 positioned in close proximity thereto would operate to cause the safety valve 39 to close and shut off the main supply of gas thereby terminating the operation of the system. The safety control valve 39 may be of any well known electrically controlled type and it is believed that a detailed showing and description is unnecessary. However, one side of the electrical mechanism of the valve is shown connected to one side of the line and the other side of the valve is connected through the switch 50 to the other side of the line.

In order to permit the complete ignition of the gas passing through the burners, it is desirable to cause a flow of gas to the burners before the air under pressure is admitted to mix with the gas. A thermally controlled electrical switch 51, commonly called a stack switch, is therefore positioned within the boiler adjacent the burners. One side of this switch is connected to one side of the line and

the other side of the switch is connected to the motor of the fan 43 and thence to the other side of the line through an electrical switch 52 which latter may preferably be of the tiltable mercury tube contactor type and actuated by the electrically controlled device 47.

When the electrically operated device 47 permits a flow of gas to the burners, it also tilts the mercury tube 52 to close the electrical circuit therethrough. After a predetermined interval, the switch 51, normally open when the supply of gas to the burners is shut off, is actuated into a closed position by means of the hot gases from the burners and completes an electrical circuit through the motor of the fan 43. When the thermostat 48 causes the electrically operated device 47 to shut off the supply of gas to the burner, the electrical circuit through the motor is simultaneously opened through the switch 52. Thus, gas is initially admitted to the burners without air until a sufficient time is elapsed to warrant a complete ignition whereafter the fan 43 forces a supply of air to mix with the gas. However, both gas supply and the air supply are terminated simultaneously by the actuation of the thermostat 48.

While but one embodiment of this invention is herein shown and described, it is to be understood that the same is not to be limited to that specific construction since various modifications may occur to those skilled in the art without departing from the spirit and scope of this invention, and we desire therefore that the structure be limited only by the showing of the prior art and the scope of the appended claims.

We claim:

1. In a gas fired boiler, upper and lower coil sections connected together for circulating a heating medium, a gas burner disposed therebetween over an extended area of said boiler and supplied with a mixture of gas and air under pressure, and means for directing the hot gases in a tortuous path about said coils whereby said hot gases are kept in a restricted state and a maximum heat transmission is obtained in said boiler.

2. In a gas fired boiler, upper and lower coil sections connected together for circulating a heating medium, a gas burner disposed therebetween over an extended area of said boiler and supplied with a mixture of gas and air under pressure, said upper coil section comprising a series of pipes arranged in a staggered vertical relation with each other to restrict the flow of the hot gases whereby a maximum of heat transmission is obtained in said boiler.

3. In a gas fired boiler, upper and lower coil sections connected together for circulating a heating medium and disposed in a substantially air-tight enclosure, a gas burner disposed between said upper and said lower

coil sections over an extended area of said boiler and supplied with a mixture of gas and air under pressure, means for directing the hot gases upwardly around the upper coil section and thence downwardly around the lower coil section whereby the flow of said hot gases is restricted and a maximum heat transmission is obtained in said boiler.

4. In a gas fired boiler, upper and lower coil sections connected together for circulating a heating medium and disposed in a substantially air-tight enclosure, a gas burner disposed between said upper and lower coil sections over an extended area of said boiler and supplied with a mixture of gas and air under pressure, a partition disposed between said gas burner and said lower coil section, and a stack connected to said enclosure adjacent said lower coil section, means for directing the hot gases from said burner first to said upper coil section and thence downwardly around said lower coil section and out said stack whereby said hot gases travel in a tortuous path and said coils obtain a maximum exposure thereto.

5. In a boiler, a plurality of coil sections for circulating a heating medium and having a discharge outlet at their lower ends, and heating means disposed adjacent the lower ends of said coil sections, each of said coil sections comprising a plurality of coils with each alternate coil lying in a vertical plane and each intermediate coil lying in a horizontal plane, each pair of adjacent coil sections lying so arranged that the said coils being in a horizontal plane are disposed substantially centrally of said coils lying in a vertical plane whereby a sluggish movement of the hot gases from said burner and therefore a maximum heat transmission is obtained in the boiler.

6. In a boiler, a plurality of coil sections for circulating a heating medium and having a discharge outlet at their lower ends, and heating means disposed adjacent the lower ends of said coil sections, each of said coil sections comprising a continuous pipe formed into coils with each alternate coil lying in a vertical plane and each intermediate coil lying in a horizontal plane, each pair of adjacent coil sections being so arranged that said coils lying in a horizontal plane are disposed substantially centrally of said coils lying in a vertical plane whereby a sluggish movement of the hot gases from said burner and therefore a maximum heat transmission is obtained in the boiler.

7. In a gas fired boiler, a coil section for circulating a heating medium and disposed in the upper portion of a substantially air tight enclosure, a gas burner disposed adjacent the lower end of said coil section and supplied with a mixture of gas and air under pressure, a stack connected to the lower portion of said enclosure, a partition extending

horizontally between said heating means and said stack connection and from one end of said boiler to a point in close proximity to the other end thereof, a partition extending vertically from the spaced end of said first mentioned partition to a point near the top of said boiler whereby the hot gases from said burner are directed upwardly over the top of said second mentioned partition and thence downwardly to said stack thus obtaining a sluggish movement of said gases.

8. In a gas fired boiler, upper and lower coil sections connected together for circulating a heating medium and disposed in a substantially air-tight enclosure, a gas burner disposed adjacent one of said coil sections over an extended area of said boiler and supplied with a mixture of gas and air under pressure, a stack connected to said enclosure adjacent the other of said coil sections, and a partition between said coil sections having a restricted opening therethrough whereby the hot gases from the burner are obstructed and a maximum heat transmission is obtained in said boiler.

In witness whereof we have hereunto subscribed our names.
